No. 764,229.

PATENTED JULY 5, 1904.

E. A. EDWARDS.
HEADLIGHT FOR LOCOMOTIVES.
APPLICATION FILED MAR. 10, 1902.

NO MODEL.

UNITED STATES PATENT OFFICE.

EDGAR A. EDWARDS, OF CINCINNATI, OHIO, ASSIGNOR, BY MESNE ASSIGNMENTS, TO METROPOLITAN TRUST & SAVINGS BANK, TRUSTEE, A CORPORATION OF ILLINOIS.

HEADLIGHT FOR LOCOMOTIVES.

SPECIFICATION forming part of Letters Patent No. 764,229, dated July 5, 1904.

Application filed March 10, 1902. Serial No. 97,606. (No model.)

To all whom it may concern:

Be it known that I, EDGAR A. EDWARDS, a citizen of the United States, residing at Cincinnati, in the county of Hamilton and State 5 of Ohio, have invented certain new and useful Improvements in Headlights for Locomotives, of which the following is a specification.

My invention relates to locomotive headlights, and especially to that class of headlights 10 in which screens are employed to reduce the glare of the light under certain conditions; and my invention consists in means by which the screen can be employed without interfering with the signal-light and without danger 15 of injury from condensed moisture and in certain features of construction fully set forth hereinafter and illustrated in the accompanying drawings, in which—

Figure 1 is a side view of a locomotive- 20 headlight casing and reflector, illustrating my invention. Fig. 2 is a front view; and Fig. 3, an enlarged section on the line 3 3, Fig. 2.

The casing A of the headlight is of any 25 proper form and proportions, containing the usual lamp and reflector (not shown) and provided on the outside with an inclined frame supporting the signal-reflector B, which receives a portion of the horizontal light-rays 30 passing through the upper portion of the opening in front of the casing and projecting them upward.

In that class of headlights in which electric 35 or other intense lights are used it is necessary to reduce the brilliancy of the light when two engines are approaching, as it interferes with the proper observation of the track and surrounding objects by the engineers, and for this reason screens or shades have been provided which can be drawn across the front 40 opening to reduce the light.

I arrange outside of the goggle-ring C, which is hinged to the front of the case A, a vertical casing 5, adapted to receive a spring-roller 6, upon which is wound a shade 7, of any suitable flexible translucent material. This casing 45 is extended so as to inclose a space at each side of the frame that will receive the

shade 7 when carried through a slit 8 in the frame and across the glass-covered opening α in front of the frame. To thus draw the shade across the opening, it is provided at the edge with a stiffening-strip 9, to the center of which is connected a draw wire or cord 10, which is passed around the guide-pulley 12, outside the casing A, and back to the cab or the 50 engineer, and this strip is properly guided by providing it at the upper end with an eye 13, receiving a guide-rod 14, that extends across the opening α . By this means the engineer can draw the shade across the opening 55 or relax the cord and allow it to move back under the action of the spring.

Inasmuch as the signal-reflector B covers the upper portion of the opening α and as it is desirable that the light-rays shall at all 60 times fall upon this reflector, the screen 7 is made only of a height sufficient to cover that portion of the opening below the reflector B, whereby this portion may be screened at will 65 without interfering with the signal-light. 70

By arranging the spring-roller and casing at one side of the structure any interference with the light or obstruction of the opening α by the casing is avoided, while any moisture which condenses on the plate 15 and 75 passes downward can escape without in any manner affecting the screen or its operation.

Without limiting myself to the precise construction shown and described, I claim—

1. The combination with a headlight-casing 80 having a front opening, of a reflector arranged at an angle in front of part of the opening to reflect a portion of the horizontal rays at an angle, and a screen and means for moving the screen to and fro across the opening below the reflector, whereby a portion of the light-rays may be reflected vertically, and the horizontal rays screened.

2. The combination of the headlight-casing 90 having a front opening and a reflector arranged at an angle across part of the opening, and a casing at one side of the frame below the reflector, a roller carrying a screen in the latter casing, and means for carrying the screen to

and fro across the opening, and a guide-rod extending across the opening to guide the screen, substantially as described.

3. The casing of a locomotive-headlight provided with a front opening and a ring supporting a glass, and with a roller-casing at one side of the ring, said ring being provided with a vertical slit communicating with the casing and a roller in the roller-casing, a screen upon the roller extending through the open-

ing and means for carrying the screen back and forth across the front opening, substantially as described.

In testimony whereof I have signed my name to this specification in the presence of two subscribing witnesses.

EDGAR A. EDWARDS
